UNITED STATES PATENT OFFICE.

RUFUS W. SCOTT, OF NEW YORK, N. Y., ASSIGNOR, BY MESNE ASSIGNMENTS, TO HEMP-HILL COMPANY, OF CENTRAL FALLS, RHODE ISLAND, A CORPORATION OF MASSACHUSETTS.

SEAMLESS STOCKING AND METHOD OF MAKING THE SAME.

Application filed January 20, 1923. Serial No. 613,856.

To all whom it may concern:

Be it known that I, RUFUS W. SCOTT, a citizen of the United States, and a resident of New York city, in the county and State of New York, have invented an Improvement in Seamless Stockings and Methods of Making the Same, of which the following description, in connection with the accompanying drawings, is a specification, like 10 characters on the drawings representing like parts.

This invention relates to seamless stockings and to the method of making the same.

In order that the principle of the invention may be readily understood, I have disclosed a single embodiment of the stocking of my invention in the accompanying drawing, wherein—

Fig. 1 is a view of the back of a stocking 20 constructed in accordance with my invention;

Fig. 2 is a view very much enlarged showing a portion of the structure of the stripe at the back of the leg of the stocking;

Fig. 3 is a plan view of a portion of a machine that may be employed in the practice of my invention, and

Fig. 4 is a view similar to Fig. 2 but showing the actual relative width of the reinforcements and the floats.

The stocking of my invention is a so-called circular knit or seamless stocking knitted upon a circular machine having means for forming the heel and toe pockets, such as narrowing and widening pickers. While any suitable mechanism may be employed in the production of the stocking, the machine should be equipped with means for introducing the main knitting yarn and also 40 for introducing a reinforcing yarn at the desired point and desirably with means for changing the stitch length as the knitting progresses.

The stocking of my invention is desirably provided at the back of the leg with a reinforcement stripe constituting in reality a duplex or two part stripe, the parts whereof are connected by short float threads lengthwise whereof, after the formation of the stocking is completed, there is run a line of sewing machine stitches constituting a mock seam and serving to tie down the said short float threads, said short float threads extending from and between the ad-

jacent inner edges of the two parts of the 55 stripe, but at the edges of said two part stripe, the long floating threads are severed and removed, so that in the completed stocking, there exist merely the short float threads which are tied down by the sewed line of 60 stitches constituting a mock seam and also constituting means for holding said short float threads in position.

Referring more particularly to the drawing, the stocking is indicated generally at 65 1, it having desirably a seamless heel 2 and a so-called seamless toe 3 with a high splice 4 of any suitable shape, the latter being provided during the knitting operation through the introduction of a reinforcing yarn which 70 may be the same yarn as that employed for knitting the longitudinal two part stripe or a substitute yarn.

The stocking may be knitted from any 75 suitable material, as, for example, silk, and beginning at or near the upper end of the stocking, as, for example, at the bottom of the so-called welt portion 5, I introduce a reinforcing yarn, such as 6, in addition to the main or body yarn 7, in any suitable 80 manner, as by providing a special yarn finger at some suitable point where the needles are divided by a special cam, so that the needles which are not to take the auxiliary 85 or reinforcing yarn are either elevated or depressed, and the auxiliary or reinforcing yarn is delivered to the other needles, which may be of any suitable number, as, for example, from ten to twenty at each side of the 90 back median line of the stocking.

In Fig. 2, I have represented the auxiliary 95 yarn at 6 and the main yarn at 7, and for convenience of illustration merely have represented the said two yarns as interknitted into the stripe for three wales only on each side of the back median line on the stocking, but have indicated the fabric as broken away. It will be understood, however, that the reinforcement stripe may be of any suitable width, and it is desirably of the full 100 length of the stocking from at least the welt to the high splice, though it may be of lesser length, but desirably extending to the high splice.

The knitted loops whereinto the auxiliary 105 yarn 6 is introduced are desirably plain loops, such as are formed in regular knitting, and between the loops into which the

reinforcing yarn is introduced is a series of wales, here shown as seven in number, into which the reinforcing yarn is not interknit-
5 ted, but past which the said yarn is floated in short lengths as indicated at 8 in Fig. 2.

Desirably each part of the duplex stripe, namely, the parts at the right and the left of the float threads 8 is in and of itself about three times the width of the set of 10 wales past which the floats 8 extend, as indicated in Fig. 4 wherein a few only of the courses are partially indicated but of a sufficient lateral extent to show the said proportion of the length of the floats and the 15 reenforced areas. My invention is not limited in this respect, but the proportion should be such as to provide a well defined stripe at each side of the non-reinforced portion where the floats 8 exist. Thus it 20 will be seen that in the preferred embodiment of my invention the length of the floats 8 is substantially less than the lateral extent of each part of the duplex stripe.

The reinforcing yarn, as indicated at 9, 25 10 in Fig. 2, is cut or otherwise severed at both outer edges of the two part stripe, so that, as stated, the long float threads, which cannot be so successfully tied down by the line of sewing machine stitches are obvi- 30 ated, thus leaving only the said short float threads 8. The number of wales past which the floats 8 extend should be sufficiently small as not to impair the effect of the stripe, but should be sufficient to permit the 35 lines of sewing machine stitches, indicated at 11, to be applied without being incorporated into the reinforced wales.

The line of sewing machine stitches may be applied in any suitable way after the 40 completion of the stocking either at the inside or at the outside of the stocking, but in either case it penetrates one or more of the wales past which the floats 8 extend, and also said floats, and tie them down against 45 the body portion of the fabric, so that they will not be displaced or present difficulty in putting on the stocking.

In Fig. 3, I have indicated a part of a machine by which the stocking may be pro- 50 duced. In said figure, I have represented a series of yarn fingers 12 for introducing the body yarn or yarns, and an additional yarn finger 13 for introducing the reinforcing yarn 6, and desirably at a point somewhat 55 removed circumferentially from the point at which the main yarn is introduced.

In order to make the reinforced stripe of the desired width, a group of heel needles having relatively short butts may be re- 60 moved and replaced by another group having special butts. A dividing cam 14 is employed to pull down all the needles except those having the special butts, so that said needles having the special butts may take 65 the reinforcing yarn from the yarn finger

13, all the other needles passing under or by said reinforcing yarn finger without taking yarn therefrom. The result is that the reinforced stripe is produced, as both the reinforcing yarn and the regular yarn are 70 knitted into the fabric at the usual knitting points, leaving the short float threads 8 which are positioned against the inner face of the fabric and are subsequently sewed down as stated. 75

In order to apply the mock seam of sewing machine stitches, the stocking is desirably folded lengthwise at or about the back median line of the stocking, and the stocking is then run through a suitable sewing 80 machine. For forming said line of sewing machine stitches, the stocking may be turned inside out, if desired, or in any suitable way the line of sewing machine stitches may be applied without turning the stocking, thus 85 avoiding an extra step in the manufacture thereof.

The stocking, although made upon a circular knitting machine simulates the full fashioned stocking made upon flat machines, 90 which latter necessarily have a seam on the back of the leg and which frequently have reinforced selvages united by said seam. The reinforcement stripe herein disclosed constitutes a simulation of the two reinforced selvages of the flat web or blank of the full fashioned stocking and the line of 95 sewing machine stitches, which does not itself penetrate the reinforced knitted loops of the stocking, simulates the actual seam 100 of a full fashioned stocking.

It will be observed that while the stocking is provided with a lengthwise running line of stitches and also with a lengthwise reinforcement stripe, said line of stitches 105 does not penetrate the interknitted structure of the stripe, but merely serves to hold down the short floats connecting the adjacent edges of the duplex stripe, in addition to its function of simulation of the actual 110 seam of the full fashioned stocking.

The short floats 8 do not themselves constitute a reinforcement and do not constitute a part of the duplex reinforcement stripe, but merely serve to unite or connect 115 the two parts of the stripe and represent the result of a practical method of forming the two parts of the stripe.

The long floats joining the outer edges of the duplex or two part stripe are prefer- 120 ably cut out after the stocking is knitted, but before the short floats are sewed down. Within the scope of my invention the reinforcing yarn may be severed in the process of knitting the stocking, at the outgoing outer edge of the duplex or two part stripe and reintroduced at the incoming outer edge 125 of said duplex or two part stripe in the next course.

Having thus described one illustrative 120

embodiment of my invention and the best mode known to me for practising the method of my invention, I desire it to be understood that although specific terms are employed, they are used in a generic and descriptive sense and not for purposes of limitation, the scope of the invention being set forth in the following claims.

Claims.

10. 1. A circular knit or so-called seamless stocking comprising a continuous knitted tubular web provided at the back with a duplex or two part reinforcement stripe composed of the main yarn and a reinforcing yarn knitted therewith throughout both parts of said stripe and floated between and joining the adjacent edges of said parts of the stripe, and a line of sewing machine stitches extending lengthwise the stocking between said adjacent edges of said two parts of the stripe, and binding said floated parts of the reinforcing yarn to the inner face of the stocking.

2. A circular knit or so-called seamless stocking comprising a continuous knitted tubular web provided at the back with a duplex or two part reinforcement stripe composed of the main yarn and a reinforcing yarn knitted therewith throughout both parts of said stripe and floated between and joining the adjacent edges of said parts of the stripe, the reinforcing yarn terminating at the outer edges of both parts of the stripe in every course of the stripe.

3. A circular knit or so-called seamless stocking comprising a continuous knitted tubular web provided at the back with a duplex or two part reinforcement stripe composed of the main yarn and a reinforcing yarn knitted therewith throughout both parts of said stripe and floated between and joining the adjacent edges of said parts of the stripe, the knitted loops between the inner edges of the two parts of the reinforcement stripe being plain loops and consisting only of the main yarn and means structurally distinct from said reinforcing yarn for securing the floats of the latter to the main yarn between the two parts of the stripe.

4. A circular knit or so-called seamless stocking comprising a continuous knitted tubular web provided at the back with a duplex or two part reinforcement stripe composed of the main yarn and a reinforcing yarn knitted therewith throughout both parts of said stripe and floated between and joining the adjacent edges of said parts of the stripe, each floated portion of the reinforcing yarn being materially shorter than the lateral extent of each part of the duplex

or two part reinforcement stripe and means structurally distinct from said reenforcing yarn for securing the floats of the latter to the main yarn between the two parts of the stripe.

5. That process of forming a circular knit or so-called seamless stocking comprising knitting a tubular leg from a main yarn and interknitting therewith at the back of the leg a reinforcing yarn in two groups of wales spaced apart to form a duplex or two part stripe, floating said reinforcing yarn across the wales intervening between the two parts of the stripe, and thereafter sewing a line of stitches lengthwise the stocking between the adjacent edges of the two parts of the stripe, thereby forming a mock seam and binding said floated parts of the reinforcing yarn to the inner face of the stocking.

6. That process of forming a circular knit or so-called seamless stocking comprising knitting a tubular leg from a main yarn and interknitting therewith at the back of the leg a reinforcing yarn in two groups of wales spaced apart to form a duplex or two part stripe, floating said reinforcing yarn across the wales intervening between the said two parts of the stripe, severing the reinforcing yarn so as to provide ends at both outer edges of the duplex or two part stripe in each course of the stripe, and thereafter sewing a line of stitches lengthwise the stripe between the adjacent edges of the two parts of the stripe, thereby binding the retained floated parts of the reinforcing yarn to the inner face of the stocking and providing a mock seam.

7. That process of forming a circular knit or so-called seamless stocking comprising knitting a tubular leg from a main yarn and interknitting therewith at the back of the leg a reinforcing yarn in two groups of wales spaced apart to form a duplex or two part stripe, floating said reinforcing yarn across the wales intervening between the two parts of the stripe for a lateral extent materially less than each part of the said two part stripe, severing the reinforcing yarn so as to provide ends thereof at the outer edges of the two part stripe in each course of said stripe, and thereafter sewing a line of stitches lengthwise the stripe between the adjacent edges of the two parts of the stripe, thereby binding said retained floated parts of the reinforcing yarn to the inner face of the stocking and providing a mock seam.

In testimony whereof, I have signed my name to this specification.

RUFUS W. SCOTT.
